UNITED STATES PATENT OFFICE.

JAMES A. WHEELER, OF SOMERSET COUNTY, NEW JERSEY, ASSIGNOR TO WILLIAM T. ELKINTON, OF PHILADELPHIA, PENNSYLVANIA.

FIREPROOF DOOR.

1,171,158.

Specification of Letters Patent. Patented Feb. 8, 1916.

Application filed May 31, 1913. Serial No. 770,809.

To all whom it may concern:

Be it known that I, JAMES A. WHEELER, a citizen of the United States, and resident of the county of Somerset, in the State of New Jersey, have invented certain new and useful Improvements in Fireproof Doors, of which the following is a specification.

This invention relates to fireproof doors of that class which are constructed of an external casing of fireproof composition material having the character of artificial lumber and inclosing metallic strengthening and bracing elements, and it has for its object to provide a simple and improved fireproof door of this character which possesses advantages especially in lightness and strength, which will be comparatively inexpensive and simple in construction, and which will afford the maximum of effectiveness and general efficiency.

In the drawings, Figure 1 is a face view of a portion of the door embodying my improvements, partly broken away to show the interior construction. Fig. 2 is a detail horizontal cross-section, on the line $x-x$, Fig. 1. Fig. 3 is a detail vertical cross-section, on the line $y-y$, Fig. 1. Fig. 4 is a detail horizontal cross-section corresponding to Fig. 2 and illustrating a modified construction. Fig. 5 is a detail vertical cross-section corresponding to Fig. 3 and illustrating the modified construction as shown in Fig. 4. Fig. 6 is a diagrammatic view in section corresponding to Fig. 4, showing the alternate spanning position of the metallic-core sheet.

Corresponding parts in all the figures are denoted by the same reference characters.

Referring to the drawings, 1 designates a frame which extends around the edge portion of the door. Said main frame is of substantially square or rectangular contour, so that it follows the outline of the door and constitutes the surrounding edge portion thereof. The frame 1 is constructed of bars or strips formed of a rigid non-metallic composition of low heat conductivity and which is fireproof and undefeatable by heat, and I prefer to use for this purpose the composition which is commercially known as "alignum" and which is constituted by a suitable filler including asbestos and combined with a fireproof binder to produce a plastic substance which is molded into shape and compressed and dried in a rigid struc-

ture. The bars or strips constituting the main frame 1 are suitably secured together so that the frame is a continuous rigid structure at the edge portion of the door and incloses a central area or space.

2—2 designate the sides of the door, which are constituted by plates or sheets of fireproof material corresponding to the fireproof characteristics of the main frame 1 and likewise formed of a rigid non-metallic composition undefeatable by heat. These side plates or sheets are respectively secured to the outer side faces of the frame 1 in any suitable manner, preferably by means of an adhesive and screws, as at 3, having their heads countersunk in recesses in the plates 2 so that the plane surface of the latter is not impaired. Said side plates or sheets, when secured in connection with the main edge-frame 1, entirely inclose the central area or space within the door, and there is thus formed an air space, as at 4, within the area surrounded by the edge-frame, whereby the fireproof quality of the door is enhanced. In the construction as just set forth, the side plates or sheets 2—2 and the main edge-frame 1 conjointly form an external casing which entirely incloses the interior metallic strengthening and bracing elements.

Within the interior area or space 4, which is surrounded by the main edge-frame 1 and inclosed by the side plates 2, are arranged at intervals blocks, 5, constituted by short bars or strips of fireproof material corresponding to the fireproof characteristics of the main frame 1 and likewise formed of a rigid non-metallic composition undefeatable by heat. The blocks or bars 5 are arranged in vertical series in alignment, and a plurality of such respective vertical aligned series are arranged in parallel position at intervals within the interior area or space 4. Said respective parallel vertical series of blocks or bars thus form a brace construction within the space 4 surrounded by the edge-frame 1, whereby the door is strengthened throughout the structure constituted by the rigid non-metallic composition elements which are undefeatable by heat and are braced against strains at a plurality of interval points. The blocks or bars 5 of the respective vertical parallel series also brace the plates or sheets 2—2 which respectively form the sides of the door, as their width on the transverse cross-

section of the door structure corresponds to the space between said plates 2. Said blocks or bars are suitably secured in connection with said side plates, preferably by means of an adhesive at the opposite surfaces of said blocks which abut against the respective side plates and by screws, as at 6, having their heads countersunk in recesses in the side plates and entering the bracing blocks. The interior parallel vertical series of the blocks or bars 5, as comprised in the improved construction as just described, not only brace and strengthen the door structure but constitute an effective means for this purpose which does not materially increase the weight of the door and therefore does not impair the characteristic of lightness which is desirable in door constructions of this class, and also do not materially reduce the area conditions of the internal central space 4 within the door. Preferably, the respective vertical series of the blocks or bars 5 extend from top to bottom of the door relative to the surrounding edge-frame 1.

Within the interior area or space which is inclosed by the side plates 2 and the main frame 1, are also arranged metallic reinforcing elements, said metallic reinforce being constituted by a sheet of metal, as at 7. The metallic reinforcing sheet 7 is preferably corrugated and occupies both the transverse and vertical extent of the internal area or space 4, with the corrugations corresponding in depth to the space between the side plates 2, whereby the apex of the projecting ribs formed by said corrugations bears against the opposite inner faces of the respective side plates 2-2, as shown at 8. In the preferred construction, the corrugated metallic sheet 7 is cut away or perforated, as at 9, to accommodate and span the respective blocks or bars 5 of the respective vertical parallel series thereof. Said sheet 7 is also preferably provided with terminal flanges, 10, at right-angles to its main portion, which flanges are therefore parallel to the inner faces of the opposite vertical strips of the main frame 1 and are secured thereto in any suitable manner, for instance by means of screws or nails, as at 11, which securing means operates to more effectively maintain the normal status of the metallic reinforcing sheet 7 and also to brace the edge-frame 1 by its connection with the metallic core constituted by said sheet. In the construction as just described, the corrugated metallic reinforcing sheet thus forms an inner metallic core for the door structure, but does not impair the open area of the air chamber 4, and it also constitutes an interior brace frame, co-operating with the blocks or bars 5, whereby the span of the side plates 2 between the edge-frame 1 is braced and said

side plates are maintained in their normal separated or relatively spaced status. It will be understood that, under some circumstances of construction, in lieu of a continuous metallic reinforcing sheet 7, the 70 reinforcing core may be constituted by a plurality of such sheets intervening between the respective vertical parallel series of the blocks or bars 5.

In Figs. 4 and 5, I have illustrated a modified construction under which, in lieu of separate blocks or bars 5 forming the respective vertical parallel series of internal braces comprised in the framework which is constituted by the rigid non-metallic fire-proof composition undefeatable by heat, said respective vertical parallel series of internal braces are formed by continuous bars or strips, as at 12, corresponding to the bars or strips of the main edge-frame 1, and in 75 this modified construction I have also illustrated the internal corrugated metallic reinforcing sheet 7 as spanning the continuous bars or strips 12 between the opposite surfaces thereof and the respective side plates 90 2 against which said surfaces abut, in lieu of the cut-away or perforated construction which is preferably employed when the separate blocks or bars 5 are used. In the modified spanning construction as just described, the metallic reinforcing sheet 7 will be further secured in normal bracing position by the screws 6 which secure the respective side plates 2-2 in connection with the respective vertical parallel series of non-metallic bracing elements. The spanning position of the metallic sheet 7, in the modified construction as just described, is preferably alternated so that the span exists at opposite sides of the door, as shown in Fig. 6. It 95 100 will be understood that the spanning arrangement of the metallic reinforcing sheet 7, as just described, may also be employed in connection with the construction in which the vertical parallel series of internal non-metallic reinforcing elements are formed of the separate blocks or bars 5, in lieu of the cut-away or perforated construction of the metallic sheet 7 as heretofore set forth.

The outer faces of the side plates 2 are 115 suitably finished, in imitation of grained wood or as otherwise desired, and an ornamental molding, as at 14, may be secured to the outer faces of said side plates 2, by means of an adhesive and screws, as at 15, 120 or otherwise, to impart any desired panel effect or other ornamental characteristics to the door surface.

The advantages of my improved door will be readily understood by those skilled in the 125 art to which the invention appertains. The improved construction provides a very simple door structure which is thoroughly braced against any strains or conditions of use and which at the same time insures the 130

characteristic of lightness which is desirable in doors of this class. The improved door is also adapted to be economically and readily manufactured, affords extreme strength and rigidity, and possesses in maximum degree all the desired fireproof characteristics, it being understood that under action of extreme heat the inclosed metallic core will be effectively protected against deformation, because of the surrounding and intervening fireproof material which constitutes the main framework and which is rigid and non-metallic and undefeatable by heat, and that therefore the door structure is effectively maintained under all circumstances and will not break down under the action of heat.

I do not desire to be understood as limiting myself to the detail construction and arrangement of parts as herein shown and described, as it is manifest that variations and modifications therein may be resorted to, in the adaptation of my invention to varying conditions of use, without departing from the spirit and scope of my invention and improvements. I therefore reserve the right to all such variations and modifications as properly fall within the scope of my invention and the terms of the following claim.

Having thus described my invention, I claim and desire to secure by Letters Patent:

An improved fireproof door of the class described, comprising a main frame con-

sisting of the bars 1 forming the edge portion of the door and surrounding the interior area or space 4, said bars being constituted by a solid substantially rectangular strip formed of a rigid non-metallic composition of low heat conductivity and undefeatable by heat, the side portions consisting of the solid sheets or plates 2 extending over the surface area of the door and secured to said edge bars and formed of a corresponding non-metallic fireproof composition, said side sheets and edge strips constituting a complete inclosure of the interior space 4 which extends across the area of the door, the internal bracing members arranged in parallel series extending vertically from top to bottom of the door between said side sheets and secured thereto, said bracing members being constituted by a solid body formed of a corresponding non-metallic fireproof composition, and the internal corrugated metallic sheet 7 extending in the interior space 4 and bracing the area of the non-metallic composition side sheets 2 between the series of internal non-metallic composition bracing members.

In testimony whereof I have signed my name in the presence of the subscribing witnesses.

JAMES A. WHEELER.
